HAROLD R. ROSENDAHL, OF MINNEAPOLIS, MINNESOTA, ASSIGNOR TO WATERS-ENTER COMPANY, OF MINNEAPOLIS, MINNESOTA, A CORPORATION OF MINNESOTA

DRAWER LOCK

Application filed January 22, 1930. Serial No. 422,591.

This invention relates to an improved device, particularly adapted for use in connection with a drawer or other member to lock it within a cabinet or other supporting member.

5 An object of the invention is to provide in combination with a drawer including a front panel adapted to be received in an aperture provided in a cabinet wall and having means for abuttingly engaging outer portions of 10 said wall adjacent to said opening to seal the joint between the cabinet wall and the drawer panel, a lock or catch for securing the drawer in its closed position, said lock comprising a member adapted to engage a portion of the 15 cabinet to lock the drawer in a closed position, and said member being adjustable whereby it may be positioned so that when the drawer is locked in closed position, the means on said drawer panel abuttingly engaged with the 20 outer surface of the cabinet wall will be held firmly thereagainst in substantially leak-proof fashion.

Other features of the invention reside in the means provided for operating the locking member; the means permitting adjustment of said member relative to the drawer panel; and, in the general construction of the device which is very simple and inexpensive whereby the device may be manufactured at 25 small cost.

In the accompanying drawings, there has been disclosed a structure designed to carry out the various objects of the invention, but it is to be understood that the invention is 30 not confined to the exact features shown as various changes may be made within the scope of the claims which follow.

In the drawings:

40 Figure 1 is a detail sectional view showing a portion of a cabinet wall and the forward portion of a drawer mounted therein and locked to the cabinet wall;

45 Figure 2 is a view similar to Figure 1 showing the drawer unlocked;

Figure 3 is a plan view of Figure 1;

Figure 4 is an enlarged detail sectional view on the line 4—4 of Figure 1;

Figure 5 is a perspective view of the locking member showing it removed from the device;

50 Figure 6 is a perspective view showing the means upon which the locking member is adjustably mounted and supported; and

Figure 7 is a perspective view showing an element adapted to support the latch-supporting member.

55 In the selected embodiment of the invention here shown, there is illustrated in Figures 1 and 2, a portion of a cabinet wall 2 having an opening 3 therein through which a drawer 4 is movable in the usual manner, as shown in Figure 2. The means for the drawer may be of ordinary construction and is therefore not shown in the drawings.

60 The drawer is shown provided with a front wall 5 and the usual side walls 6. A panel 7 having an overhanging marginal flange 8, is secured to the drawer 4 and spaced therefrom by suitable supporting members 9. The panel 7 is adapted to be received in the wall opening 3 in which position the flange 8 will abuttingly engage the portion of the cabinet wall adjacent to the opening 3, as best shown in Figure 1. The front wall 5 of the drawer is provided at its 65 upper edge with a flange or ledge 11 preferably extending in a forward direction and having its ends secured to the supporting members 9. This flange strengthens the front wall 5 of the drawer 4.

80 A feature of this invention resides in the means provided for locking the drawer in the closed position shown in Figure 1. To thus retain the drawer in closed position, a locking member 12, preferably of U-shaped 85 cross section, as shown in Figures 4 and 5, is mounted upon a supporting member 13 having one end pivotally connected to the front wall 5 of the drawer by means of a clip 14 secured to the drawer wall as shown. 90

5 A suitable pin 16 connects the member 13 to the clip 14 and preferably has a suitable spring 17 mounted thereon adapted to constantly urge the supporting member 13 in an upward direction, as will be clearly understood by reference to Figure 1.

10 The locking member 12 has a depending end portion 18, the upper portion of which is adapted to engage the inner corner 19 of the wall opening 3, when the drawer is locked as shown in Figure 19. When the portion 18 of the locking member is thus engaged with the wall 2, the flange 8 surrounding the panel 7 will be firmly seated against outer portions 15 of the cabinet wall, as hereinbefore stated, and thus seal the opening 3.

20 Another feature resides in the means provided whereby the locking member 19 may be relatively adjusted with respect to the flange 8 of the drawer panel 7. To thus adjust the locking member, the spaced side walls 21 thereof are each provided with an elongated opening or slot 22 adapted to register with threaded apertures 23 provided in the 25 supporting member 13. Suitable screws 24 secure the locking member 12 to the supporting member 13. To relatively adjust the locking member 12 upon the member 13, the screws 24 are loosened sufficiently to 30 permit the member 12 to be relatively moved upon the supporting member 13, and, when positioned thereon so as to hold the flange 8 firmly against the outer surface of the cabinet wall, the screws 24 are tightened, 35 whereupon the member 12, when in the position shown in Figure 1, will lock the drawer to the cabinet wall in dust-proof relation. The depending end portion 18 of the locking member 12 is so shaped that when it is engaged with the corner 19 of the cabinet wall 2, it will have a wedging effect thereon which will constantly tend to draw the flange 8 firmly against the outer surface of the cabinet wall. This will readily be understood 40 by reference to Figure 1, wherein it will be noted that the end portion 18 of the member 12 is angularly disposed with reference to the inner surface of the cabinet wall 2.

45 The means provided for actuating the locking member 12 to permit the drawer to be withdrawn from the cabinet, comprises a handle 25 having spaced legs or side members 26, each apertured to receive a pivot pin 27, which pins are retained in operative positions by means of a face plate 28, preferably having integral sockets 29 therein adapted to receive the pins 27, as best shown at the right hand side of Figure 3. The inner ends 31 of the handle legs 26 are shown 50 bent upwardly and have a rod 32 interposed therebetween, as shown in Figure 3. The ends of this rod 32 are suitably secured to the end portions 31 of the legs 26 of the handle, by such means as nuts 33. The rod 32 55 is adapted to engage a depending portion 34

provided upon the supporting member 13, as shown in Figures 1 and 2.

60 The above described parts are so oriented that when an operator grasps the handle 25 and exerts a slight outward pull thereon, the handle legs 26 will be oscillated upon the pins 27 thereby causing the rod 32 to be moved downwardly against the portion 34 of the supporting member 13, resulting in the locking member 12 being moved out of locking engagement with the corner 19 of the drawer wall, as clearly shown in Figure 2. As the operator continues to pull on the handle 25, the drawer may be moved to a position exteriorly of the cabinet as will readily be noted 65 by reference to Figure 2. To close the drawer, it is only necessary to shove it back into the cabinet, whereupon the locking member 12 will automatically move into locking engagement with the corner 19 of the cabinet 70 wall, because of the action of the spring 17.

75 The particular lock featured in this invention has been found particularly useful in connection with cabinets adapted for storing foods, where it is essential that the drawers 80 be locked in leak-proof relation so as to preserve the food stored therein. The structure is very simple and inexpensive in construction and readily lends itself to manufacture in quantity production whereby the cost 85 thereof may be reduced to a minimum.

90 I claim as my invention:

95 1. The combination with a cabinet having an opening in a wall thereof and a drawer 100 slidably mounted therein and provided with a front panel bounded by an outwardly projecting flange adapted to engage outer surfaces of the cabinet wall to close said opening, of a lock comprising a member pivotally mounted upon a wall of the drawer and having a depending portion, a handle comprising an arm traversing an opening in said panel and adapted for rocking movement therein, means on said arm engaging said depending portion, means constantly urging 105 said member and arm upwardly, and a plate secured to said member and having a portion adapted to engage an inner portion of the cabinet wall to lock the drawer in position 110 therein. 115

120 2. The combination with a cabinet having an opening in a wall thereof and a drawer slidably mounted therein and provided with a front panel bounded by an outwardly projecting flange adapted to engage outer surfaces of the cabinet wall to close said opening, of a lock comprising a member pivotally mounted upon a wall of the drawer and having a depending portion, a handle comprising spaced apart arms traversing openings in said panel, means pivotally supporting said arms in said panel openings, means on said arms engaging said depending portion where by when said handle is operated, said member 125 will be depressed, a U-shaped plate mounted 130

upon said member and having a portion adapted to engage an inner portion of the cabinet wall whereby the drawer may be locked in position therein, and means permitting relative movement of said plate upon said member whereby the flange may be caused to firmly seat against the outer surfaces of the cabinet wall.

In witness whereof, I have hereunto set my
10 hand this 14th day of January, 1930.

HAROLD R. ROENDAHL.
